(57) **CLAIM**

The ornamental design for an electrical connector as shown and described.

DESCRIPTION

3. Electrical connector

3.1 : Front

3.2 : Back

3.3 : Left

3.4 : Top

3.5 : Bottom

3.6 : Right

3.7 : Perspective

FIG. 3.1 is a front elevational view of an electrical connector. FIG. 3.2 is a back elevational view thereof. FIG. 3.3 is a left elevational view thereof. FIG. 3.4 is a top plan view thereof. FIG. 3.5 is a bottom plan view thereof. FIG. 3.6 is a right elevational view thereof. FIG. 3.7 is a perspective view thereof.

The Dash-Dash broken line represents the portions of the electrical connector that form no part of the claimed design. The Dash-Dot broken line represents the claim boundary and form no part of the claimed design.

1 Claim, 7 Drawing Sheets
